UNITED STATES PATENT OFFICE.

EDWARD SCHAEFER, OF ST. LOUIS, MISSOURI, ASSIGNOR TO THE MISSOURI LAMP AND MANUFACTURING COMPANY, OF SAME PLACE.

DESIGN FOR A BODY FOR CIGAR-LIGHTERS.

SPECIFICATION forming part of Design No. 28,522, dated May 3, 1898.

Application filed January 15, 1898. Serial No. 668,828. Term of patent 3½ years.

To all whom it may concern:

Be it known that I, EDWARD SCHAEFER, a citizen of the United States, residing at St. Louis, in the State of Missouri, have invented and produced a new and original Design for a Body for a Cigar-Lighter, of which the following is a specification.

The figure is a front elevation of the cigar-lighter, showing my new design.

As shown in the drawing, the leading or material feature of my design for a body for a cigar-lighter consists of a substantially spherical tank, a handle extending downwardly from the tank, a body extending upwardly from the tank, a perforated substantially hemispherical body extending upwardly from the wick-raiser, and a substantially hemispherical body extending upwardly from the perforated body.

Referring by numerals to the drawing, the substantially spherical tank 1 has an annular bead 2 extending horizontally around its cen-

ter. The pear-shaped handle 3 extends downwardly from the bottom of the tank 1. The vertical annular face 4 extends upwardly a short distance from the tank 1 and is surmounted by the bell-shaped body 5, which in turn is surmounted by the annular flange 6. The vertical annular body 7 extends upwardly from the flange 6. The bead 9 rests upon the body 7, and the perforated substantially hemispherical body 10 rests upon said bead. The vertical face 11 extends upwardly from the body 10 and is surmounted by the substantially hemispherical body 12, and the body 12 is in turn surmounted by the bell-shaped body 13.

I claim—

The design for a body for a cigar-lighter as herein shown and described.

EDWARD SCHAEFER.
